(57) **CLAIM**

The ornamental design for a display for electronic device, as shown and described.

DESCRIPTION

FIG. 1 is a front perspective view of a display for electronic device showing our new design;
FIG. 2 is a front view of the display for electronic device of FIG. 1;
FIG. 3 is a rear view of the display for electronic device of FIG. 1;
FIG. 4 is a left-side view of the display for electronic device of FIG. 1;
FIG. 5 is a right-side view of the display for electronic device of FIG. 1;
FIG. 6 is a top plan view of the display for electronic device of FIG. 1; and,
FIG. 7 is a bottom plan view of the display for electronic device of FIG. 1.
The oblique lines shading in FIGS. 1, 2, 4, 5, 6, and 7 indicates reflective surfaces.
